UNITED STATES PATENT OFFICE.

ULYSSES S. DE MOULIN, OF GREENVILLE, ILLINOIS.

INITIATION DEVICE.

Application filed July 23, 1926. Serial No. 124,517.

This invention relates to an initiation device, the object being to provide a structure having the general appearance of a flower holder but which, by means of a control device will be shattered or displaced by the explosion of a concealed cartridge so that the liquid or other contents of the container will be scattered in all directions much to the surprise and amusement of those in close proximity to the structure.

A further object is to provide a device of this character which is simple and compact in construction and can be so applied to a table or other structure in a way that the working parts will be concealed.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a perspective view of the device, a portion of the table to which it is applied being shown.

Figure 2 is a vertical transverse section.

Figure 3 is a section on line 3—3, Figure 2.

Referring to the figures by characters of reference 1 designates a cylindrical block containing an expansion chamber 2 open at the top. This block has an extension 3 at the bottom thereof and extending into the side of the extension is a cartridge receiving bore 4 the inner end of which opens upwardly as at 5 into the bottom of the expansion chamber. The bore 4 and its upwardly extending portion 5 cooperate to provide an explosion chamber.

An ear 6 is extended laterally from the extension 3 and pivotally mounted thereon is a lever 7 constituting a trigger. A spring 8 is mounted on the pivot 9 of the trigger and has its respective ends attached to the ear 6 and trigger 7 respectively so that the striking shoulder 10 of the trigger is normally positioned against the extension 3 at or close to the bore 4. A leaf spring 11 is secured to the bottom of the extension 3 and is inclined upwardly and outwardly so as to project into the path of the trigger. A stud

12 is extended downwardly from the trigger and is adapted, when the trigger is retracted, to engage one edge of the spring 11 as shown by broken lines in Figure 3, thereby to hold the trigger set.

A plunger 13 can be connected to the outer end portion of spring 11, this plunger having an abutment 14 slidable in an opening 15 and the table top T. Thus by depressing the button spring 11 will be depressed and the trigger 7 released.

Another means for actuating the spring to release the trigger can be in the form of a cord 16 connected to the lower end of the plunger 13 and slidable within one or more guides 17 so as to be extended to a point at any desired distance from the table so that by pulling the cord the trigger will be released.

Block 1 is fitted snugly within an opening 18 formed in the table top and an annular flange 19 formed on the block is attached to the table top by means of screws or the like.

Block 1 is fitted snugly within an opening 18 formed in the table top and an annular flange 19 formed on the block is attached to the table top by means of screws or the like. A paper container for holding water or other suitable material is adapted to be placed on the table and over the upper end of the block 1. This container has been indicated at C. The container, if desired, can be used as a vase for holding cut flowers as well as water and when in position, will arouse no suspicion of the presence of the mechanism constituting this invention. A blank cartridge, indicated at B is inserted in the bore 4 and the trigger is retracted so as to be held by the spring 11. The device is then ready for use. One or more persons can be seated at the table and when it is desired to operate the structure the button 14 is depressed or the cord 16 is pulled. Trigger 7 will be released and its spring 7 will propel it violently against the cap of the cartridge. Thus the cartridge will be exploded and the gases generated will rush into the chamber 2 with sufficient force to shatter the container C and throw the water in all directions.

It is important that the explosion chamber be L-shaped as by forming it of the bore 4 and its upwardly extending portion 5. Thus the full force of the explosion is first received by the wall of the portion 5 before the gases enter the chamber 2.

What is claimed is:

1. An initiation device including a supporting structure, a container thereon, and means below and concealed by said structure

- and container for shattering the container and distributing its contents over the supporting structure and adjacent thereto, said means including a block having an expansion chamber, there being an angular explosion chamber opening into the expansion chamber for receiving a cartridge, a trigger, and remote controlled means for releasing the trigger to explode the cartridge.
- 10 2. An initiation device including a block having an expansion chamber open at one end, means for connecting the block to a supporting structure, the open end of the block constituting means for engaging and holding a container concealing the open end of the block, an extension on the block having

an angular explosion chamber opening into the expansion chamber, said explosion chamber having a portion opening through one side of the extension to receive a cartridge, a spring actuated trigger pivotally connected to the extension of the block, a spring secured to the extension and projecting into the path of the trigger for engagement therewith to hold the trigger set, and means operable at a point remote from the block for shifting said spring to release the trigger and explode the cartridge.

In testimony that I claim the foregoing as my own, I have hereto affixed my signature.

ULYSSES S. DE MOULIN.
